OTHER PUBLICATIONS

Three Photographs of Container Provided by Applicant in use in the United States on or before Mar. 1, 2014 (Exhibit A).

Primary Examiner — Derrick Edward Holland

Assistant Examiner — Janice Julia Patyk

(74) *Attorney, Agent, or Firm* — King & Partners, PLC

(57) **CLAIM**

The ornamental design for a container, as shown and described.

DESCRIPTION

FIG. 1 is a front perspective view of a container, showing our new design.

FIG. 2 is a left side view of the container of FIG. 1, and the right side view being a mirror image.

FIG. 3 is a front view of the container of FIG. 1.

FIG. 4 is a rear view of the container of FIG. 1.

FIG. 5 is a top plan view of the container of FIG. 1; and,

FIG. 6 is a bottom plan view of the container of FIG. 1.

The broken lines in the figures illustrate the portions of the design that form no part of the claimed design.

1 Claim, 5 Drawing Sheets
